(57) **CLAIM**

The ornamental design for the inflatable chair as shown and described.

DESCRIPTION

FIG. 1 is a top perspective view of the inflatable chair showing the new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof;

FIG. 7 is a bottom view thereof; and,

FIG. 8 is a bottom perspective view thereof.

The broken line showing on the inflatable chair is for the purpose of illustrating portions of the inflatable chair that form no part of the claimed design.
